(57) CLAIM

The ornamental design for a mirror cabinet as shown and described.

DESCRIPTION

FIG. 1 is a top perspective view of a mirror cabinet showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of mirror cabinet in open position.

Broken lines in the drawings depict portions of the mirror cabinet that form no part of the claimed design.

1 Claim, 6 Drawing Sheets
